Patented Jan. 20, 1976

238,502

HOLDER FOR ARTICLES SUCH AS CANDLES, CANDY OR SIMILAR ARTICLES

James Lloyd Thrush, Lancaster, Ohio, assignor to Anchor
Hocking Corporation, Lancaster, Ohio

Filed Oct. 23, 1973, Ser. No. 408,371

Term of patent 14 years

Int. Cl. D26—01

U.S. Cl. D48—2

FIG. 1 is a side elevational view of a holder for articles such as candles, candy or similar articles, showing my new design;

FIG. 2 is a top view thereof;

FIG. 3 is a bottom view thereof;

FIG. 4 is a bottom view of another embodiment of my design;

FIG. 5 is a sectional view taken along line 4-4 of FIG. 4 in enlarged scale;

FIG. 6 is a sectional view taken along line 6-6 of FIG. 3;

FIG. 7 is an elevational view of my design showing the article in the form of a bowl;

FIG. 8 is an exploded view of the article shown in FIG. 6; and

FIG. 9 is a top view of one of the articles shown in FIG. 6.

I claim:

The ornamental design for a holder for articles such as candles, candy or similar articles, substantially as shown and described.
